[57] CLAIM

The ornamental design for a combined sensor cartridge for a fluid analyte analyzer and monitoring module, as shown and described.

DESCRIPTION

FIG. 1 is a top, and right side perspective view of a combined sensor cartridge for a fluid analyte analyzer and monitoring module, in separated condition;

FIG. 2 is a top plan view thereof, in connected condition;

FIG. 3 is front perspective view thereof;

FIG. 4 is a left side elevational view of the sensor cartridge;

FIG. 5 is a right side elevational view of the sensor cartridge;

FIG. 6 is a left side elevational view of the monitoring module separated from the sensor cartridge;

FIG. 7 is a right side elevational view of the sensor cartridge separated from the monitoring module;

FIG. 8 is a rear elevational view of FIG. 3; and,

FIG. 9 is a bottom plan view thereof.

UNITED STATES PATENT AND TRADEMARK OFFICE
CERTIFICATE OF CORRECTION

PATENT NO. : Des. 375,555
DATED : November 12, 1996
INVENTOR(S) : Douglas R. Savage, et. al.

It is certified that error appears in the above-identified patent and that said Letters Patent is hereby corrected as shown below:

Title page, **DESCRIPTION, FIG. 3**, insert --a-- before the word "front";

Signed and Sealed this

Eighteenth Day of November 1997
